UNITED STATES PATENT OFFICE.

ROBERT H. SMITH, OF COLUMBUS, GEORGIA.

AUTOMATIC CYLINDER COCK.

Application filed July 25, 1922. Serial No. 577,375.

To all whom it may concern:

Be it known that I, ROBERT H. SMITH, citizen of the United States, residing at Columbus, in the county of Muscogee and State 5 of Georgia, have invented certain new and useful Improvements in Automatic Cylinder Cocks, of which the following is a specification.

This invention relates to an improved automatic cylinder cock, being particularly designed for use upon locomotives, and seeks, as one of its principal objects, to provide a device of this character wherein when the steam pressure in the locomotive cylinders 10 is relieved, the cock will automatically open for draining the cylinders.

A further object of the invention is to provide a cylinder cock wherein, when steam is admitted to the locomotive cylinders, the 15 cock will be automatically closed.

And the invention has as a still further object to provide a cock wherein, when desired, the cock may be manually opened.

Other and incidental objects will appear 20 hereinafter.

In the drawings:

Figure 1 is a fragmentary side elevation showing my improved cock in connection with a locomotive.

30 Figure 2 is a vertical sectional view through the cock.

Figure 3 is a vertical sectional view at substantially right angles to Figure 2, and

35 Figure 4 is a transverse sectional view on the line 4—4 of Figure 2, looking in the direction of the arrows.

In carrying the invention into effect, I employ a casing 10 provided at its upper end with a nipple 11 and leading downwardly 40 within the casing from said nipple are oppositely disposed exhaust passages 12 defining a centrally disposed core 13 within the casing. At their lower ends, the passages 12 enter a chamber 14 and threaded through the bottom wall of the casing is a plug 15 closing said chamber, this plug being provided with a frusto-conical inner end face 16. Formed in the core from the lower end 45 thereof is an axially disposed valve chamber 17 at the lower end of which the core is provided with a beveled valve seat 18 and leading from the chamber through a suitable web 19, is an outlet passage 20 opening through the wall of the casing. Arranged 50 to coact with the valve seat 18 of the core is a valve 21 having a stem 22 extending up-

wardly within the valve chamber 17 and radiating from said stem are spaced vanes 23 slidably coacting with the wall of the chamber for centering the valve therein. Formed through the casing 10 and through the core 13 above the valve chamber 17, at substantially right angles to the outlet passage 20, is an opening or slot 24 communicating with the valve chamber and slidably 60 through said opening is an operating bar 25 in which is formed an elongated notch 26 having a cam face 27 sloping gradually to the lower edge of the bar.

In use, a pair of the cocks is employed 70 upon each cylinder of the locomotive. In Figure 1 of the drawings, I have conventionally shown a locomotive at 28, the cylinder at the adjacent side of the locomotive being indicated at 29. As will be observed, the nipples 11 of the drain cocks are threaded 75 through the wall of the cylinder at its lower side and in mounting said cocks, the openings 24 therethrough are brought into alinement so that the bar 25 may extend freely 80 through the openings of both cocks. Accordingly, the notch 26 and cam face 27 upon the bar are duplicated at each cock and mounted upon the rear end of the cylinder is a bracket 30 upon which is pivoted a lever 85 31 connected at its lower end with the rear end of the bar. Suitably mounted within the locomotive cab is a pivoted operating lever 32 and extending between the lower end of this lever and the upper end of the lever 31 90 is a reach rod 33.

Normally, the lever 32 will stand at the position shown in Figure 1, when the notches 26 in the bar will be disposed over the valve stems 22 of the cocks so that said stems may rise into said notches and permit the valves 21 to move to closed position in engagement with the seats 18. Accordingly, when steam is admitted to the cylinder 29, the steam will flow through the passages 100 12 of the cocks to enter the chambers 14 beneath the valves, the steam striking the frusto-conical faces 16 of the plugs 15 to be deflected upwardly thereby against the valves for lifting the valves to closed position. Steam pressure beneath the valves will then serve to hold the valves closed until the supply of steam to the cylinder is cut off. When this occurs, the valves 21 105 will drop by gravity to rest against the plugs 15 so that the cylinder may then drain through the passages 12 of the cocks,

the valve chambers 17 and outlet passages 20. Accordingly, as will be seen, the valves will be automatically closed by steam pressure and will automatically open by gravity when the steam pressure is relieved. To manually open the valves of the cocks, the lever 32 is rocked forwardly which will, as will be at once understood, result in slidably shifting the bar 25 forwardly. The cam faces 27 of the bar will thus be caused to ride over the upper end of the valve stems for depressing the valves, as shown in Figure 3, to open position. Thus, the cylinder may be drained notwithstanding the presence of steam pressure therein and, of course, when the lever 32 is again actuated for returning the bar 25 to its normal position, the valves will again close under the influence of steam pressure therebeneath.

Having thus described the invention, what is claimed as new is:

In a cylinder cock, a casing provided at its upper end with a nipple and formed with

passages leading downwardly within the casing at opposite sides thereof and connected at their lower ends by a chamber common thereto, said passages defining an intervening core having an axial valve chamber opening at its lower end into the former chamber and the casing being formed with an outlet passage extending across one of said first mentioned passages as well as with a slot extending through the casing and through said core at substantially a right angle to said outlet passage, a downwardly opening valve slidable in said valve chamber but normally held elevated in closed position by steam pressure, the valve being provided with a stem to project into said slot, and a bar slidably fitting through said slot and provided with an inclined face to coact with the valve stem for depressing the valve to open position when the bar is shifted.

In testimony whereof I affix my signature.

ROBERT H. SMITH. [L.S.]
